Primary Examiner — Barbara Fox*Assistant Examiner* — Kimberly Barnes(74) *Attorney, Agent, or Firm* — Chris J. Katopis(57) **CLAIM**

The ornamental design for a display screen with baseball keyboard graphical user interface, as shown and described.

DESCRIPTION

The FIGURE is a front view of a display screen with baseball keyboard graphical user interface showing the new design.

The broken lines shown in the drawings illustrate portions of the display screen with baseball keyboard graphical user interface and form no part of the claimed design.
